UNITED STATES PATENT OFFICE

MARK CARTER, OF LOS ANGELES, CALIFORNIA

DESIGN FOR A DOOR GRILL

Application filed October 1, 1930. Serial No. 37,099. Term of patent 7 years.

To all whom it may concern:

Be it known that I, MARK CARTER, a citizen of the United States, and resident of Los Angeles, in the county of Los Angeles, State of California, have invented a new, original, and ornamental Design for a Door Grill, of which the following is a specification, reference being had to the accompanying drawing, forming a part hereof.

I claim.

The ornamental design for a door grill as shown and described.

In witness that I claim the foregoing I have hereunto subscribed my name this 26th day of September, 1930.

MARK CARTER.
